Specification for Design.

Patented Aug. 1, 1922.

Application filed February 27, 1922. Serial No. 928. Term of patent 7 years.

To all whom it may concern:

Be it known that I, JOHN F. SHOEMAKER, a citizen of the United States, and a resident of Chicago, in the county of Cook and State of Illinois, have invented a new, original, and ornamental Design for Safety Paper for Checks, Drafts, or Negotiable Instruments, of which the following is a specification, reference being had to the accompanying drawing, forming part thereof.

The figure is a plan view of a portion of the sheet of paper embodying my new design.

I claim:

The ornamental design for safety paper for checks, drafts, or negotiable instruments as shown.

Des Moines, Iowa, February 18, 1922.

JOHN F. SHOEMAKER.
